CLAIM

The ornamental design for a tray and/or liner, as shown and described.

DESCRIPTION

FIG. 1 is a perspective view of a tray with a liner inserted therein;

FIG. 2 is a perspective view of the tray;

FIG. 3 is a front view of the tray;

FIG. 4 is a back view of the tray;

FIG. 5 is a first side view of the tray;

FIG. 6 is a second side view of the tray;

FIG. 7 is a top view of the tray;

FIG. 8 is a bottom view of the tray;

FIG. 9 is a perspective view of the liner for the tray;

FIG. 10 is a front view of the liner for the tray;

FIG. 11 is a back view of the liner for the tray;

FIG. 12 is a first side view of the liner for the tray;

FIG. 13 is a second side view of the liner for the tray;

FIG. 14 is a top view of the liner for the tray; and,

FIG. 15 is a bottom view of the liner for the tray.

The broken lines are for illustrative purposes only and form no part of the claimed design.
